UNITED STATES PATENT OFFICE.

HENRY ROBERT JAGELS, OF PHILADELPHIA, PENNSYLVANIA.

SOUNDING APPARATUS FOR HOLDS OF VESSELS.

SPECIFICATION forming part of Letters Patent No. 621,251, dated March 14, 1899.

Application filed January 12, 1898. Serial No. 666,387. (No model.)

To all whom it may concern:

Be it known that I, HENRY ROBERT JAGELS, of Philadelphia, in the State of Pennsylvania, have invented certain new and useful Improvements in Sounding Apparatus for the Holds of Vessels, whereof the following is a specification, reference being had to the accompanying drawings.

Hitherto vessels have been provided with a removable plug upon the deck, giving access to the pump-well in which the suction-pipe leading from the pump extends to the bottom of the hold. When it is desired to ascertain the depth of water in the hold, the aforesaid deck-plug is removed and a bar (usually provided with a scale indicating fractions of feet) is manually lowered to the bottom of said well. Said bar when withdrawn indicates by the extent of its wet surface the depth of water in the well, and consequently in the hold with which said well communicates. The aforesaid operation is most difficult to perform at the time it is most necessary—i. e., during a storm.

It is the object of my present invention to provide an automatic signaling apparatus which is primarily adjusted to the maximum depth of bilge-water usually found in vessels under ordinary circumstances, said apparatus being so constructed that an increase beyond the ordinary depth of said water shall lift a float, complete an electric circuit, and thereby operate a signal located at any convenient point, whereby the attention of the person having control of the pumps may be attracted. Such an arrangement is of obvious advantage in that it relieves the crew from the responsibility and labor incident to the operation of the ordinary apparatus above described and prevents the accidental water-logging of the vessel by accumulation of bilge-water from unknown leaks in the hold.

In the accompanying drawings, Figure 1 shows a convenient embodiment of my invention as applied to a vessel pump-well, the wiring connections for the signal being indicated diagrammatically. Fig. 2 is a central sectional view of the electric switch operated by the rise of the float. Fig. 3 is a central sectional view of the coupling for the float-rod.

In said figures, A is a frame, preferably of wood. B is a bracket mounted upon said frame and adapted to support a switch-mechanism contained in a casing C at the extremity of said bracket. Said switch mechanism is adapted to be operated as aforesaid by the float D, the latter being provided with a central stem D' and being mounted for vertical reciprocation between brackets B' and B² upon said frame A. The lower bracket B² is provided with a tubular leg b², which rests upon the bottom of the well X and serves as an additional support for said bracket. Connection is made from the float-stem D' to the switch mechanism in the casing C by means of the slide-rod E, which is mounted for reciprocation in the stuffing-box e of said casing, being supported by the brackets B' and B².

In order to facilitate the primary assembling of the parts in proper adjustment, I provide a coupling-sleeve F, adapted to connect the float-stem D' and the slide-rod E, said sleeve being securely affixed to each of said members conveniently by pins, as shown in section in Fig. 3. To prevent the displacement of the slide-rod E when for any reason said float is subsequently disconnected by removal of the pins of the coupling-sleeve, &c., I prefer to provide said rod with a collar e, said collar serving to uphold said rod in its normal position by contact with the bracket B'.

As shown in Fig. 1, the electric circuit aforesaid may comprise a battery G and suitable wiring connections H and H', connecting said battery with the signal I and the switch mechanism C. It is obvious that any convenient form of switch mechanism may be used, but I prefer that which is shown in section in Fig. 2, comprising a casing C, wherein are mounted the terminals h and h' of the respective wiring connections H and H', which extend through the bushings c'c' in the cover C' of said casing, connecting within the latter to said terminals, which are mounted upon the insulating-plate C^X, secured to said cover. The terminal h' is a resilient metal plate which normally occupies the position indicated in Fig. 2, but is adapted to be thrust into contact with the terminal h, and thus complete the electric circuit through the latter

when the rod E is raised by the float D, up-lifted by the increase of bilge-water, as aforesaid.

As shown in Fig. 2, a space e^x may normally exist between the upper extremity of said rod E and the lower face of the terminal h' , so that the former may rise and fall a certain extent without closing the electric circuit to operate said signal I. When, however, the water x lifts the float upward, shifting the slide-rod E beyond the limit of its idle movement, the electric circuit is established by contact of the terminal h' with the terminal h , and the signal I is operated, as aforesaid.

I am aware that it is not broadly new to operate an electric signal by means of a switch mechanism such as that which I have shown in the casing C. I believe, however, that it is broadly new to employ such a well-known form of circuit and switch mechanism for the purpose which I have described and actuate said switch mechanism by the means which I have described. I therefore do not desire to

limit myself to the precise construction of my invention which I have shown and described, 25 as it is obvious that various modifications may be made therein without departing from the spirit of my invention.

I claim—

The combination with the pump-well of a 30 vessel, of a frame secured to the wall of said well, a slide-rod mounted in said frame, a float mounted in said frame, a stem upon said float, a detachable coupling for said stem and said slide-rod, an electric switch mechanism 35 mounted upon said frame, in alignment with said slide-rod, and an electric circuit connecting with said switch mechanism, and comprising a source of electricity and a signal adapted to be operated by the movement of 40 said switch mechanism, substantially as set forth.

HENRY ROBERT JAGELS.
